UNITED STATES PATENT OFFICE.

JOSEPH A. BURGESS, OF WORCESTER, MASSACHUSETTS.

SEWER-GAS TRAP.

SPECIFICATION forming part of Letters Patent No. 227,411, dated May 11, 1880.

Application filed March 15, 1880. (No model.)

To all whom it may concern:

Be it known that I, JOSEPH A. BURGESS, of the city and county of Worcester, and State of Massachusetts, have invented a new and 5 useful Improvement in Sewer-Gas Traps; and I do hereby declare the same to be described in the following specification and represented in the accompanying drawings, of which—

Figure 1 is a side elevation, Fig. 2 a longitudinal section, and Fig. 3 a transverse section, of a trap of my improved kind, the latter section being taken through the rear part of the box or chamber in order to represent the air-jet orifices of discharge.

15 The trap as described is for the purpose of preventing gas from a sewer from passing into an apartment or building by means of a pipe for discharging waste-water from a sink or other device in said apartment or building, the nature of my invention being duly set forth in the claims hereinafter made.

In the drawings, A denotes an elongated box or chamber, having its bottom *a* somewhat inclined to its top, or to the horizon, the 25 said box having entering the upper part of its lesser or rear end a waste-water induct or pipe, B. The box also is provided at the lower part of its front or greater end with an educt, C, for conveying the waste-water from the box 30 to a drain or sewer. Furthermore, the box has extending across it from side to side of it, and from its top to within a short distance of its bottom, a deflector or inclined partition, D. It also has, or may have, between the said inclined partition and the educt C a vertical 35 cross-partition, E, which extends upward from the bottom to a height greater than the distance between the bottom of the box and that of the inclined partition.

40 Over the vertical partition, and leading out of the top of the box, is a gas-duct, F, which may be a spout leading from a roof-gutter, and serving not only to carry off the sewer-gas from the box, but to discharge water from such 45 roof directly into the box. Against the lesser end of the box or chamber, and encompassing the induct B thereof, is an air-supply apparatus or jet, G, consisting of a drum provided with a pipe, b, for conducting air into it, and 50 also having leading out of it and through the end of the box a series of apertures, *c c e*, arranged in a circle about the waste-water induction-pipe B of said end of the box.

In some cases, or where it may not be desira-

ble to have water stand in the box on both 55 sides of the inclined partition, the other or lower or vertical partition may be dispensed with; but generally I prefer to have both partitions within the chamber.

On waste-water being discharged from a sink 60 into the box or chamber and out of the educt thereof, air will be induced to flow from the air-jet into the chamber, and especially around the waste-water induct. Such air and waste-water will impinge against the inclined partition, and by it will be deflected downward, and will pass underneath it toward the educt, the waste-water escaping through the latter, and the air facilitating the escape through the spout of any sewer-gas which may have passed 65 into the box or chamber.

With the two partitions in the box, water will remain within the space between the vertical partition and the rear or lesser end of the chamber, and will rise to a level with the 75 upper edge of said partition, and consequently above the lower edge of the inclined partition, and with such partition will prevent any sewer-gas from passing from the front to the rear side of the inclined partition, and thence into 80 the waste-water pipe and sink thereof, such gas escaping from the box through the spout.

As air will be drawn into the box by means of the air-jet while waste water may be passing into and out of the box, such air, whether 85 the vertical partition is used or not, will aid in ventilating the box and facilitating the escape of waste-water.

I claim as my invention as follows, viz:

1. A ventilating sewer-gas trap consisting 90 of the box or chamber A, the roof-water spout or induct F, the waste-water induct B and educt C, the deflecting-partition D, and the air-induction jet G, all arranged and to operate substantially as specified.

2. The combination of the box or chamber 95 A, the two partitions D E, the waste-induct B and educt C, and the air-induction jet G, all arranged essentially as explained.

3. The combination of the box or chamber 100 A, the roof-water induct F, the waste-water induct B and educt C, the two partitions D E, and the air-jet G, all arranged substantially as set forth.

JOSEPH A. BURGESS.
